UNITED STATES PATENT OFFICE

129,324

DESIGN FOR A CERAMIC ELEMENT FOR GAS HEATING STOVES AND THE LIKE

Roy A. Dudley, Huntington, W. Va., assignor to
Armstrong Products Corporation, Huntington,
W. Va., a corporation of West Virginia

Application July 31, 1940, Serial No. 94,073

Term of patent 14 years

To all whom it may concern:

Be it known that I, Roy A. Dudley, a citizen of the United States, residing at Huntington, in the county of Cabell and State of West Virginia, have invented a new, original, and ornamental Design for a Ceramic Element for Gas Heating Stoves and the like, of which the following is a specification, reference being had to the accompanying drawing, forming part thereof.

The drawing shows in Figure 1 a perspective view of a ceramic element for gas heating stoves and the like showing my new design.

Fig. 2 is a front elevational view of the design.
Fig. 3 is a vertical sectional view from front to

rear, on line 3—3 of Fig. 6 looking from right to left.

Fig. 4 is a plan view of a section taken on line 4—4 of Fig. 2.

Fig. 5 is a sectional view on line 5—5 of Fig. 4 looking in the arrow direction.

Figure 6 is a section on the line 6—6 of Fig. 4 looking in the arrow direction.

Fig. 7 is a bottom plan view of the new design for the ceramic element.

I claim:

The ornamental design for a ceramic element for gas heating stoves and the like, as shown.

ROY A. DUDLEY.
